UNITED STATES PATENT OFFICE.

HENRY A. HOUSE, OF BRIDGEPORT, CONNECTICUT.

VAPOR BURNER AND IGNITER.

SPECIFICATION forming part of Letters Patent No. 559,895, dated May 12, 1896.

Application filed September 5, 1895. Serial No. 561,580. (No model.)

To all whom it may concern:

Be it known that I, HENRY A. HOUSE, a citizen of the United States, residing at Bridgeport, in the county of Fairfield and State of Connecticut, have invented certain new and useful Improvements in Vapor Burners and Igniters, of which the following is a specification.

This invention relates to certain new and useful improvements in vapor-burners; and it consists substantially in such features of construction, arrangement, and combinations of parts as will hereinafter be more particularly described.

The invention has reference more particularly to that class of vapor-burning apparatus in which a liquid fuel is vaporized in a retort communicating with the burner; and the object of the invention is the more perfect ad- mixture of the air and vapor for the production of a richer and better flame.

A further object of the invention is the provision of means whereby as the pressure changes from low to high the point of ignition or focal point of the flame is altered with respect to the retort or generator and the escape of the vapor permitted to take place in greater volume and at a much greater velocity.

A further object of the invention is to provide greater facility for cleaning the burner and valves as they become obstructed from deposits of residue from the oils, as well also as to increase the certainty of ignition of the burner under all circumstances or conditions.

Further objects of the invention will hereinafter more fully appear, when taken in connection with the accompanying drawings, in which—

Figure 1 is a central vertical sectional elevation of a vapor-burner constructed and arranged in accordance with my invention. Fig. 2 is a side view of the burner proper, representing the same as it appears exteriorly. Fig. 3 is a cross-sectional view on the line $x-x$ of Fig. 2, and Fig. 4 is a top or plan view of the burner proper.

My invention is capable of a great many different embodiments, but preferably I resort to the construction and arrangement of parts substantially such as I have herein illustrated.

A represents a retort-generator of any suitable construction, but preferably provided with a continuous channel a , extending 55 throughout the interior of the same, and the said retort or generator being constructed of any suitable refractory material capable of withstanding a considerable amount of heat. The said retort or generator A is provided 60 with a central opening b , for a purpose to be hereinafter described, and at one side an opening c is provided for the entrance or insertion of the end of the liquid-fuel-supply pipe B, while at the opposite or some other part of 65 said retort or generator a similar opening e is provided for the entrance or insertion of the upper end of the pipe C, which extends downward and conveys or supplies the burner with vapor from the said retort or generator. 70

Before beginning to describe the construction and arrangement of the parts of my improved burner proper I desire to state that one of the principal advantages of the construction thereof is that I am enabled to burn 75 crude petroleum as well as heavy residual oils which are not ordinarily capable of being burned because of the great number of thick oil globules present therein, and which do not readily vaporize under ordinary conditions 80 as have heretofore existed.

A further advantage of my improved burner is that I am enabled to change the intensity of the flame against the retort, and whenever there is any tendency to a cooling down, such 85 as is apt to occur with increased pressure or velocity of the vapor, the operation is such as to permit of the escape of the vapor in increased volume and thereby counteract such tendency. 90

My improved burner is capable of being constructed in a great many different ways; but preferably I employ the construction such as I have herein shown.

D represents the chamber of the burner, in 95 the side of which at f is provided an opening for receiving the lower end of the pipe C, which leads from the retort or generator and which conveys the vapor to the burner. The top of the said chamber D is formed with an 100 opening or port g , preferably slightly conical in form, while projecting upward from the base h of said chamber is a hollow post i , in which is held or supported a vertical rod or

stem *j*, which extends upward to a suitable height and which, as will be observed, is formed in its sides with several longitudinal grooves *k*, which begin at about the point *l* 5 and extend along the rod or stem for the rest of its length.

E represents a hollow cone, open at both top and bottom and formed or provided centrally with a sleeve *F*, which fits and works upon the 10 rod or stem *j*, and which sleeve terminates at its lower end in a valve *m*, corresponding in shape to the opening or port *g* in the top of the chamber *D* of the burner, while at the upper end of said sleeve *F* an opening or port *n* is 15 provided for the passage or escape of the vaporized liquid fuel in the manner hereinafter described. The said central sleeve is of course provided with a longitudinal opening by which to enable the sleeve to fit and move 20 upon the rod or stem *j*, and the said sleeve is united with the walls of the cone *E* by means of a suitable number of internal radial ribs or wings *n'*, which may comprise an integral part. These said ribs or wings *n'* are separated by 25 spaces which permit of the escape or passage of the vapor upward through the cone, as will hereinafter be described, and from the construction explained it will be seen that the said cone is capable of vertical movement upon 30 the rod or stem. The said central sleeve *F* preferably extends above the top of the cone *E* when the latter is in its downward or lowermost position, and fitting upon the same and having an independent movement with respect thereto is a weighted supplemental sleeve *o*, which terminates at its upper end or 35 portion in a number of vertically-disposed ribs *p*, which are separated by spaces *q*, while pendent within said upper portion of the said 40 weighted supplemental sleeve is a valve *r*, which, when the sleeve is lowered upon the upper end of the central hollow sleeve *F*, serves to completely close the port *n* in the upper end of the latter. It is obvious that 45 when the combined cone *E* and sleeve *F* are in their downward or lowermost positions no vapor can escape through the port *g* in the top of the chamber *D* of the burner, and it is likewise apparent that when the weighted 50 supplemental sleeve *o* is lowered upon the upper end of the said sleeve *F* the valve *r* will also prevent the escape of any vapor through the port *n* in the top of said sleeve *F*. Normally the valves *m* and *r* close their 55 respective ports, and they are separately caused to be lifted by the pressure of the vapor, as will be hereinafter explained. Supported in any suitable manner above the cone *E*, but preferably by means of rods or posts *s*, 60 extending upward from the base of the burner, is an additional or supplemental cone *G*, which is of larger dimensions than said cone *E*, and the said supplemental cone is also open both at the top and bottom, and it is hollow 65 throughout. Projecting inwardly therefrom at or near the base is a number of wings or ribs *H*, which are notched at *t*, so as to con-

veniently rest upon the upper edge of the cone *E* in such manner as to be lifted by the latter in any upward movement thereof 70 caused by the increased pressure or velocity of the vapor fluid passing through the burner. The purpose of the said supplemental cone in addition to aiding in the production of induced air-currents is to increase the resistance in proportion to the increased volume or pressure of the vapor fluid. The port *n* in the top of the sleeve *F*, together with the valve *r*, comprise what I call a "primer" or "low-pressure" burner, while the port *g* in 75 the chamber *D*, together with the valve *m*, operating in conjunction therewith, constitute what I term a "main" or "high-pressure" burner, the two burners being so combined that when the valve of the main port 80 is closed and the vapor is passing from the retort to the said chamber *D* at about a pressure, say, of five pounds to the square inch the valve of the said primer-burner will be elevated against the resistance of the weight 85 of the supplemental sleeve *o* sufficiently to permit the escape of the vapor through the said port *n* in quite a small flame, but yet at the proper degree of pressure or velocity. As long as the vapor maintains this low degree 90 of pressure the said primer-burner will be constantly supplied by passage of the vapor through the sleeve *F* along the grooves of the stem *k*, and in practice it has been found that the flame thus produced is sufficiently great 95 to maintain a constant vaporization of the liquid fuel in the retort or chamber *A*. It is evident that while the flame is burning induced currents of air are produced which follow the directions indicated by the arrows 100 and the admixture of the vapor and air is such that the results attained are most perfect. As more oil is introduced to the generator or whenever the pressure is increased from any cause, with a tendency to a cooling 105 of the burner on account of imperfect vaporization due to the increase of volume, then the valve *m* is lifted and the focal point or point of ignition of the flame takes place, or is changed from the primer-burner to the port 110 *g* of the main burner, which allows the increased volume to escape through the port *g* at a much greater velocity—say about ten pounds to the square inch—while at the same time the said focal point or point of ignition 115 of the flame is somewhat lower down with respect to the retort or generator. In this way I allow for the escape of the increased volume which cannot escape through the port of the primer-burner fast enough to be burned 120 against the surface of the generator or retort with the desired effect, and at the same time I counteract the tendency of any cooling down of the said retort or generator which any increase of supply of oil thereto would 125 be apt to cause. As the valve *m* is lifted together with the cone *E*, it is evident that the port of the primer-burner is thereby closed, and then whenever the pressure of the vapor 130

in the burner has again become reduced to substantially its original pressure the said valve *m* will be lowered by the weight which it carries, and as long as the pressure continues at about, say, four pounds to the square inch the said primer-burner will continue to burn in the manner heretofore explained. It is evident that when the pressure increases and the valve of the main port *g* is raised the 5 said supplemental cone *G* will also be lifted from its supports by the rising of the cone *E*, and the resistance will always be in proper proportion to the supply or volume of vapor. Thus it will be seen that my improved burner 10 proper comprises a primer or low-pressure burner, or a port for the vapor under low pressure, controlled by a valve, as well as a main or high-pressure burner or port also controlled by a valve, the valve in each instance being weighted in such manner as to be lifted the one when the pressure and velocity attain a certain degree, and the other when such velocity and pressure have attained a certain higher point or degree.

25 From the construction and operation explained I am enabled to maintain the action of the burner equally well under a very considerable variation in horse-power, and the certainty of action is greatly increased as 30 compared with other devices of a similar nature. It will be observed that the upper or supplemental cone *G* is readily detached from the lower cone, and also that when the valve of the primer-burner is removed the lower 35 cone *E*, as well as the central sleeve thereof, is readily lifted from position. In this way increased facility is had for cleaning the valves and other parts as they become obstructed from accumulations of oil residue. The several 40 parts of my improved burner are of course intended to be of refractory material, by which to absorb and retain a considerable amount of heat, and it is evident that the same is not liable to easy fracture and that it can be manufactured at comparatively small 45 cost. The parts can be readily cleaned without detaching any of the pipes, and it will be understood that various changes and modifications in the general construction and arrangements could be resorted to.

50 In order to readily ignite the burner at any time after the flame may have been extinguished, as well as to constantly maintain the said burner in an ignited or lighted condition 55 whatever may be the variation in the fluid supply, I provide a special form of igniting device which while capable of a great many different embodiments is preferably of the form shown in Fig. 1, wherein *J* represents a chamber or receptacle of suitable form and dimensions, the same being preferably slightly contracted at *K*, and then terminating downwardly in an extended cone *L*, which fits 60 within the central opening *b* of the retort or generator *A*, and which is preferably coincident with a central vertical line drawn through the burner, the lower end whereof

being in sufficiently close proximity to the burner or upper supplemental cone thereof to constantly relight the burner at such time 70 when it may be desirous of restarting the same or whenever from any accidental cause the burner may have become extinguished. The said contracted portion *K* of my improved igniter device rests upon the upper surface of 75 the retort or generator at *u*, and the chamber *J* is provided with a number or series of transverse grate-bars *v*, upon which is supported a crushed or broken mass of refractory material, such as fire-brick and asbestos fiber, 80 a quantity of which is placed within the chamber *J* through a suitable opening *M* at the top thereof, which is closed by a cap or plug *N*. The cone *L* is of course hollow, and in the sides thereof I provide at suitable points 85 or intervals a number of perforations or openings *w*, while in the sides of the contracted portion *K* of the said igniter device, as well as in the top of the chamber *J*, I provide similar openings *w'* and *w''*, respectively. The 90 lower end of the hollow conical tube *L* by extending down through the retort to a point near the escape of vapor from the burner will allow considerable of the flame to pass up into and through the loose mass of refractory 95 material in the chamber *J*, which mass becomes exceedingly hot and is raised to an incandescent heat, and by virtue of being enclosed within the chamber in the manner described the said mass of refractory material 100 retains its heat for a very long time after the burner has been extinguished. The flame from the burner passes into the mass of refractory material both through the mouth of the conical tube *L* as well as the perforations 105 *w* thereof, and the openings or perforations *w'* and *w''* also permit of the entrance of flame and heat to such mass. In this way the burner may be extinguished at any time either by cutting off the supply of vapor to 110 the burner by use of suitable valves or by any other suitable way, and it may be allowed to so remain for quite a considerable length of time, and as the vapor is again allowed to be conducted to the burner a sort 115 of circulation will be produced above the burner by the heat of the refractory mass, and the tendency of the vapor will be to flow upward through the conical tube into and through the refractory material, whereby the 120 said vapor is superheated and caused to be ignited by contact with the hot surroundings and an explosion takes place in a downward direction toward the point of escape of the vapor from the burner and the latter becomes 125 lighted or ignited in an obvious manner. This is the operation and effect of my improved igniter device, even though there may be a strong draft in an upward direction, and it has been found in practice that the same 130 operation takes place under varying circumstances and conditions. As a means of protecting the pipes *B* and *C* from intense heat at points adjacent to where they enter the

generator I prefer to provide the latter with depending deflecting portions x x , which, however, form no part of my present invention.

5. My invention will be thoroughly understood without further description, it is thought, and, as before stated, I do not limit myself to the precise details of construction and arrangement of the several parts, since 10 various different embodiments could be resorted to and still be within the scope intended to be embraced.

What I claim is—

1. In a vapor-burner, a burner comprising 15 a low-pressure port and valve and a high-pressure port and valve, substantially as described.

2. In a vapor-burner, a burner comprising a low-pressure port and a weighted valve and 20 a high-pressure port and a weighted valve, substantially as described.

3. In a vapor-burner, a burner comprising a low-pressure port and weighted valve, and a high-pressure port and weighted valve, and 25 an additional weight adapted to be lifted as the valve of said high-pressure port is lifted, substantially as described.

4. In a vapor-burner, a burner comprising a low-pressure port and weighted valve, a 30 high-pressure port and weighted valve located beneath said low-pressure port and valve, and a hollow cone supported above and adapted to be lifted by said high-pressure valve, substantially as described.

35 5. In a vapor-burner, a burner comprising a low-pressure port and valve, a high-pressure port and valve, a hollow cone adapted to be lifted by said high-pressure valve, and an elevated or superposed hollow cone adapted to be lifted by the first-named cone, substantially as and in the manner described.

40 6. In a vapor-burner, a burner comprising a low-pressure port and valve, a high-pressure port and valve, the two ports being in communication with each other, and suitable weights for each of said valves, substantially as described.

45 7. In a vapor-burner, a burner comprising a low-pressure port and weighted valve, a high-pressure port and weighted valve, the two ports being in communication with each other, a hollow cone carried by said high-pressure valve, and an additional superposed cone adapted to be lifted by the first, substantially as shown and in the manner described.

50 8. In a vapor-burner, a burner comprising the chamber D having enlarged or high-pressure port, and the longitudinally-grooved rod 60 or stem extending upwardly through said port to a suitable height, a sleeve movable on said stem or rod having in its upper end a low-pressure port and terminating at its lower end with a valve adapted to the high-pressure 65 port, the cone E carried by said sleeve, the supplemental weighted sleeve and the

low-pressure valve carried by said latter sleeve, the whole operating substantially as shown and described.

9. In a vapor-burner of the character described the combination of the low and high pressure ports and their weighted valves, and the enlarged superposed hollow cone held by independent supports and adapted to be lifted, substantially as shown and for the purpose described. 70

10. In a vapor-burning apparatus, the combination with a suitable retort-generator having a central opening, and a suitable burner arranged beneath the same, of an igniter comprising a chamber filled with refractory material and having a tubular portion projecting through said opening in proximity to the burner, substantially as shown and for the purpose described. 80 85

11. In vapor-burning apparatus, the combination with a suitable retort having a central opening, and a burner arranged beneath said opening, of an igniter comprising a chamber filled with refractory material and having a perforated tubular portion projecting through said opening in proximity to the burner, substantially as described. 90

12. In vapor-burning apparatus, the combination of a retort and burner, of an igniter comprising a chamber having a grate and filled with a refractory material or mass, the said igniter being perforated at different points and having a conical perforated tubular portion extending below the retort in proximity to the burner, substantially as described. 95 100

13. In a vapor-burner, a burner comprising a low-pressure port and valve, and a high-pressure port and valve, in combination with an igniter device arranged in proximity to said burner, substantially as described. 105

14. In a vapor-burner, a burner comprising a low-pressure port and weighted valve, and a high-pressure port and weighted valve, in combination with an igniter device arranged in proximity to said burner, substantially as described. 110

15. In a vapor-burner, a burner comprising a low-pressure port and valve, and a high-pressure port and valve, in combination with a retort or generator, and an igniter device heated by said burner and arranged in proximity thereto, substantially as described. 115

16. In a vapor-burner, an igniter device comprising the chamber J having the contracted portion K, and terminating downwardly in a conical perforated tubular portion, substantially as described. 120

In testimony whereof I have signed my name to this specification in the presence of two subscribing witnesses. 125
